UNITED STATES PATENT OFFICE.

ALDUS FISHER, OF MALVERN, PENNSYLVANIA.

SWITCH-LOCKING MECHANISM.

Application filed August 9, 1921. Serial No. 490,873.

To all whom it may concern:

Be it known that I, ALDUS FISHER, a citizen of the United States, residing at Malvern, in the county of Chester and State of Pennsylvania, have invented certain new and useful Improvements in Switch-Locking Mechanism, of which the following is a specification.

One object of my present invention is to provide mechanism which will positively lock a railroad track switch in open and closed positions and which will be of a far simpler and more durable construction than mechanism previously employed for this purpose or now in use.

Another object is to so construct my improved mechanism that it cannot be accidentally displaced or broken by trains passing over the track.

Another object is to so construct my improved mechanism that it can be quickly and easily adjusted to suit various requirements in the opening of the switch from the adjacent rail and will be capable of locking the switch in any of its possible open or closed positions. Thus my improved mechanism is particularly well adapted for use on any railroad irrespective of the requirements of the opening desired between the switch and the adjacent rail.

These objects, and other advantageous ends which will be described hereinafter, I attain in the following manner, reference being had to the accompanying drawings in which—

Figure 1 is a fragmentary perspective view of a railroad track and switch; the same illustrating my invention in a position capable of locking the switch either in its open or closed position,

Figure 2 is a longitudinal section taken through my improved mechanism showing the parts in a position for example to lock the switch in an open position,

Figure 3 is a view of similar character to Figure 1 illustrating certain of the parts having been moved into a position during the unlocking of the switch and during the movement of the means effective to throw the switch into a closed position,

Figure 4 is a view of similar character to Figures 2 and 3 illustrating the parts having been moved into an unlocked position to permit the complete throwing of the switch.

Figure 5 is a view of similar character to Figures 2, 3 and 4 showing the parts in a position during the throwing action of the

switch and before the switch has been entirely closed,

Figure 6 is a view of similar character to Figures 2 to 5 inclusive illustrating said parts in a position having effected the closing of the switch and the locking of the switch in its closed position, 60

Figure 7 is a transverse section taken on the line 7—7 of Figure 4, 65

Figure 8 is a top plan view illustrating my improved mechanism; the adjustable plates being illustrated in a position with the locking apertures close together and capable of being moved apart as for example 70 as illustrated in Figure 4.

Figure 9 is an enlarged section taken on the line 9—9 of Figure 8,

Figure 10 is a perspective view showing the under surface of one of said plates, and 75

Figure 11 is a perspective view of a locking member which I preferably employ.

Referring to the drawings 12 represents a railroad track having rails 13 and 13^a mounted on ties 14; said track having switches 15 in the form of rails which are adapted to be moved as a unit toward and from the rails 13 and 13^a to effect the switching of a train for example from said track to another track in the usual manner. 80

My invention consists of a base 16 in the form of a plate which is secured to the top surfaces of two adjacent ties 14 preferably by tap bolts 17 as shown in Figures 1, 7 and 8. This base has undercut ribs 18 depending from its lower surface and providing slideways 19 which extend in a direction transversely of the length of the track; said ribs occupying a space between said adjacent ties. 90

A box or case 20, which is preferably made of metal, has laterally extending flanges 21 slidably positioned within the slideways 19 so that said box is free to slide with respect to the base in a direction transversely of the track. The top 22 of the box 20 has a hole 100 23 therein adapted to always be in registry with a slot 24 in the base 16.

Two locking plates 25 are positioned on the upper surface of the base 16 and have slots 26 therein through which extend bolts 27; said 105 bolts being secured to the base 16 and serving to permit said plates 25 to be moved toward or from each other for purposes of adjustment as will hereinafter be more fully described and it will be noted that by tightening the bolts 27 that the locking plates 25 can be secured to the base. In order to in-

sure against any accidental movement of the plates 25 relatively to the base, I preferably roughen or provide the engaging surfaces of the plates 25 and base 16 with teeth 28 which intermesh and as shown in Figure 9. If it is desired to move the plates 25 relatively to the base, it is necessary to loosen the bolts 17 to such extent as to allow the plates 25 to be first lifted out of mesh with the teeth of the base 16, after which the plates 25 can be adjusted and again permitted to engage the base 16 so that when the bolts 27 are tightened the plates 25 will be securely locked to the base 16. It will be noted that each of the plates 25 has a notch or recess 29 and an adjacent tongue 30; the arrangement being such as to provide shoulders 31 which preferably abut each other as shown in Figures 1 and 8.

20 The plates 25 respectively have apertures 32 and 32^a therein which extend entirely therethrough and communicate with the slot 24 in the base.

25 A pivot rod 33 is mounted in the box 20 and supports a locking member 34. This locking member has two locking dogs 35 and 36 which are spaced apart and project upwardly through the hole 23 in the box 20. The dog 36 under certain conditions for example as shown in Figure 2 is adapted to move into the hole 32^a in one of the plates 25 and the dog 35 under certain conditions hereinafter described is adapted to move upwardly within the hole 32 of the other plate 25 as shown in Figure 5. The lower portion of the member 34 has depending legs 37 and 38 which are spaced apart. The surface 39 between the legs 37 and 38 being preferably curved as illustrated.

40 The box 20 has holes 40 in its opposite ends through which slide an operating rod 41; the bottom of the box preferably being channeled or grooved as shown at 41^a to permit the portion of the rod 41 which extends through the box, to slidably rest therein. With the parts thus far described it will be noted that the box 20 under certain conditions can slide relatively to the base 16 and the rod 41 can slide relatively to the box 20.

45 The rod 41 at a portion within the box 20 has a block or lug 42 secured thereto which serves in a double capacity namely to rock the member 34 and also to move under the leg of the member which has been raised due to its rocking movement. Thus the block 42 serves as an actuator and as a supporting table.

50 The rod 41 is adapted to be moved longitudinally by any suitable means such for example as by the usual lever mechanism in railroad operating towers. The rail switch portions 15 are connected by a tie bar 43; this tie bar being secured as for example by a bolt 44 to a portion 45 of the box 20.

55 Considering that the switch 15 is locked

in its open position as shown in Figures 1, 2 and 8 with the dog 36 extending into the aperture 32^a of the one locking plate 25 with the block 42 of the rod 41 positioned under the leg 38, if it is desired to throw 70 the switch into and lock the same in its closed position, the rod 41 is moved lengthwise toward the left viewed from Figure 2; the first part of the movement of this bar serving to move the block 42 from under 75 the leg 38 and into engagement with the leg 37 of the member 34; it being noted that when the member 34 is swung into the position as shown in Figure 2 that the leg 37 will be in the path of movement of the block 80 42. A continued movement of the rod 41 in said direction will cause the block 42 to engage the leg 37 of the member 34 and swing said member on its pivot rod 33 from the position shown in Figure 3 so that the 85 dog 36 will move out of the aperture 32^a and the dog 35 will move upwardly into engagement with the bottom surface of the latter mentioned plate 25; thus limiting said swinging movement of the member 34. 90

95 A continued movement of the rod 41 will move the box 20 in the direction toward the rail 13 and since the box 20 is connected by the tie bar 43, the switch portions 15 of the rail will be moved toward the rail 13. This action occurs due to the fact that since the member 34 can no longer swing on its pivot shaft, said member serves as a medium to impart the movement of the block 42 to the box and the box will slide in the sideways 100 19 on the base 16. As soon as the dog 35 registers with the hole 32 in the other plate 25, the member 34 can then swing so that the dog 35 will move upwardly into the aperture 32 as shown in Figure 5 and a continued movement of the block 42 and operating rod 41 will cause the block 42 to move under the leg 37 of the member 34 and thereby hold the dog 35 in the aperture 32 as shown in Figure 6; thus locking the 110 switch portions 15 in their shifted position. The operating rod 41 in the form illustrated is provided with screw threaded portions with nuts 46 and 47 thereon so that after the block 42 has moved under the 115 leg 37, the nut 46 will engage the adjacent end of the box and limit the further movement of the operating rod with respect to the box. If it is desired to vary the amount of throw of the switch the plates 25 can be 120 moved toward or from each other as the case may be so that the apertures 32 and 32^a will be moved either closer together or further apart to allow a greater or less movement to the box between the unlocking 125 action and the locking action as is obvious from the construction illustrated and above described. It will of course be understood that when the switch portions are to be moved in an opposite direction the rod 16 130

is moved in an opposite direction or for example toward the right viewed from Figure 6; the first action being to move the block 42 from under the leg 37 of the member 34 and into engagement with the leg 38 of said member whereby the member will be swung to withdraw the dog 35 out of the slot 32 and move the dog 36 upwardly into engagement with the under surface of the adjacent plate 25. Then the block 42 will be operative to move the box until the dog 36 registers with the aperture 32^a. Then the dog 36 will swing upwardly into the aperture 32^a and the block 32 will again move under the leg 38 and the nut 47 will engage the adjacent end of the box 20. It will be also noted that tension is applied to the operating rod 41 due to its connection with the operating means in the tower or other place which includes means for throwing the switches. Thus accidental movement of the rod 41 is prevented.

It will be noted that by a single continuous movement of the operating rod 41 in one direction the switch will be unlocked and moved into a shifted position and then locked in said shifted position. Vice versa when the operating rod is moved continuously in an opposite direction the switch will be unlocked and moved in an opposite direction and then again locked in its shifted position.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. Mechanism of the character described adapted to move and lock a switch, said mechanism including pivoted locking means; means for bodily carrying said locking means; means connecting said carrying means with said switch; fixed means for locking engagement with said locking means; and operating means adapted to move said locking means on its pivot into and out of locking engagement with a portion of said fixed means and for moving said carrying means, when the locking means is moved out of locking engagement with said fixed means to effect movement of the switch from one position to another, said fixed means having another portion for locking engagement with said locking means, said operating means being adapted, after said movement of the carrying means, to move said locking means into locking engagement with said latter portion of said fixed means,

said fixed means being made up of parts respectively including said portions, said parts being adjustable relatively to each other; substantially as described.

2. Mechanism of the character described adapted to move and lock a switch, said mechanism including fixed means having apertures spaced apart; a locking member; means forming a carrier for said locking member and movable relatively to said first means; an operating rod having a portion adapted to move said locking means relatively to its carrier whereby portions of the locking means can be moved into and out of said apertures, said portion of the operating rod being adapted to move said carrier relatively to said first means when the locking means is out of registry with said apertures; and means connecting said carrier with said switch; substantially as described.

3. Mechanism of the character described adapted to move and lock a switch, said mechanism including fixed means having apertures spaced apart; a locking member; means forming a carrier for said locking member and movable relatively to said fixed means; an operating rod, said locking member having dogs spaced apart and leg portions spaced apart, said operating rod having a portion adapted to engage said leg portions and swing said member so that its dogs can be respectively moved into and out of said apertures and to move under said leg portions to hold either of the dogs within its aperture, said portion on the operating rod also serving to move said carrier relatively to said fixed means through the medium of engagement with the locking member when moving the latter from a position within one of the apertures to a position engaging within the other of the apertures; and means operatively connecting said carrier with the switch; substantially as described.

4. Mechanism of the character described adapted to move and lock a switch, said mechanism including fixed means having apertures spaced apart; a locking member; means forming a carrier for said locking member and positioned below said fixed means; an operating rod, said locking member having dogs spaced apart and leg portions spaced apart, said operating rod having a portion adapted to engage said leg portions and swing said member so that its dogs can be respectively moved into and out of said apertures and to move said leg portions to hold either of the dogs within its aperture, said portion on the operating rod also serving to move said carrier relatively to said fixed means by swinging said locking member so that its dogs are both below said fixed means and then being adapted to move the carrier through the medium of engagement with the locking member; and means

operatively connecting said carrier with the switch; substantially as described.

5. Mechanism of the character described adapted to move and lock a switch, said mechanism including a fixed base having a slot; a box slidably mounted below said base and having a hole registering with said slot in the base; means secured relatively to said base and having apertures in register with and above said slot; a locking member pivotally mounted in the box and having dogs spaced apart thereof which can be swung upwardly through the hole and slot; and an operating rod slidable 10 within the box and having a projecting portion thereon, said locking member having leg portions spaced apart and adapted to be engaged by said projecting portion of the operating rod whereby the locking member can be swung so that one of the dogs will engage within one of said apertures and so that said portion of the operating rod can move under one of the legs to hold said dog in said position, said portion of 15 the operating rod being adapted to swing the locking member into a position with both of the dogs below said first means whereby said operating rod can move the box through the medium of engagement 20 with the locking member so as to move the other of the dogs into registry with and to enter the other aperture, said portion of the operating rod being adapted to move under the other leg of said locking member 25 and thereby hold said latter mentioned dog in said position; substantially as described.

6. Mechanism of the character described adapted to move and lock a switch, said mechanism including members having apertures; switch shifting means; locking means carried by said shifting means and movable into locking engagement with said members by entering either of said apertures; a fixed support; and means adjustably securing said 30 members to said fixed support whereby said apertures can be moved toward or from each other; substantially as described.

7. Switch locking mechanism including a base; a box mounted to slide in the base; 35 a tie bar connected to the box and connecting the switch rails; locking plates secured to the base; a locking member pivotally mounted in the box and having dogs adapted to engage with the locking plates; an

operating rod adapted by movement, in either direction, to release one of the locking dogs from engagement with a locking plate, to slide the box thereby actuating the tie rod to close or open a switch, and to force the other dog into engagement with a locking plate.

8. Switch locking mechanism including a slotted base; a box mounted to slide in the base; a tie bar connected to the box and connecting the switch rails; locking plates secured to the base and having openings communicating with the slot in the base; a locking member pivotally mounted in the box and having dogs adapted to engage the locking plates; an operating rod adapted by movement, in either direction, to release one of the locking dogs from engagement with a locking plate to slide the box thereby actuating the tie rod to close or open a switch, and to force the other dog into engagement with a locking plate.

9. Switch locking mechanism including a base; a box mounted to slide in the base; a tie bar connected to the box and connecting the switch rails, locking plates secured to the base; a locking member pivotally mounted in the box and having dogs, adapted to engage with the locking plates, and beveled faced depending lugs, and an operating rod having a lug adapted to engage with the lugs on the locking member to alternately release one locking dog from engagement and force the other into engagement with a locking plate.

10. Switch locking mechanism including a base; a slidable member; a tie rod connecting the sliding member with the switch rails, locking plates movably secured to the base; means for holding the locking plates in selected positions; a pivotally mounted locking member having dogs adapted to engage with the locking plates; and an operating rod adapted to actuate the locking member to alternately release one dog from engagement and force the other into engagement with a locking plate.

In testimony whereof I have signed my name to this specification in the presence of two subscribing witnesses.
